ATTORNEY

UNITED STATES PATENT OFFICE

CYRUS WILLIAM RICE, OF PITTSBURGH, PENNSYLVANIA

CONTROL APPARATUS FOR BLOWDOWN WATER

Application filed July 30, 1927. Serial No. 209,594.

This invention is to provide a combination apparatus for limiting the continuous flow of blowdown water from a boiler, and means for obtaining samples of water for testing purposes.

A further object is to provide a device which shall include a housing or casing having a pipe connected therewith for introducing water under pressure, a pipe adapted for connection with a boiler, a four-way cock adapted to control the flow of water between these pipes, and to control the flow thru a strainer and thru an adjustable element having a reduced port thru which water may pass to and thru a duct in the casing, and thence thru another four-way cock, to a pipe connected or adapted for connection with a main blowdown pipe,—this cock last named also controlling flow thru a port leading to a connection for discharging wash water and for sampling blowdown water.

A further object is to provide means for washing the blowdown pipe back to the boiler, when desired, and for washing out the strainer, and for directing the flow for other purposes, as herein indicated.

With the foregoing and other objects in view, the invention consists in the novel construction and arrangement of elements described, illustrated and claimed, it being understood that modifications may be made within the scope of the claim without departing from the spirit of the invention.

In the drawing forming part of this application,

Figure 1 shows the device in vertical section.

Figure 2 is a view in edge elevation.

Figure 3 is a view looking from the lower side in Figure 1.

The main casing or housing is designated 10, and is provided with a bore 11 in alinement with port or bore 12, a chamber 13 being positioned between the bore and said port 12. A four-way valve or cock is designated 14, and controls the four ports in the sleeve 15, these ports being adapted for registration with the bores 11 and 12, and likewise with ports or bores 16 and 17.

Water under pressure may be admitted

thru pipe 18, which pipe is in communication with bore 12, and a pipe 19 has connection, or is adapted to have connection, with a boiler.

A chamber 20 receives a threaded plug 21 having a bore or cutaway portion 22 and a port 23 in communication with the bore 22. A strainer 25 positioned in chamber 20 is connected with the plug at 26, and a channel 27 communicates with chamber 20, with bore 11, and with the bore 27' closed by plug 28. A port 29 communicates with bores 11, 27 and 27'.

Adjacent to portion 29 is a chamber for receiving a sleeve 30 providing four ports for four-way valve 31 having in the body thereof a bore or channel providing ports as shown. A bore 32 is in communication with pipe 33 adapted to connect with a main continuous blowdown pipe, and port or channel 34 is in communication with pipe 35 leading or adapted to lead to a point of discharge, for drawing off a sample of blowdown water for testing purposes, and for discharging waste water resulting from washing the strainer with water from pipe 18.

Within the casing or housing 10 is a channel 38 extending in the direction or directions shown and adapted to communicate with one of the ports of sleeve 30. This channel 38 is in alinement with port 39 closed by plug 40.

A main plug 42 having an outer angular portion is provided with a chamber 44 and with an entrance port 45 adapted to register with channels 38 and 39. The chamber 44 has threaded connection with plug 46 having an outer annular shoulder adapted to engage the end of plug 42, and having a bore or orifice 47 in axial alinement with bore or channel 48, so that when plug 42 is in a given position, there is a continuous passage between chamber 20 containing the strainer, and thence thru the element just described to channel 38.

The plug 46 and the walls of the bore 47 thereof are subject to considerable wear on account of the high velocity of the blowdown water therethru, and this plug and plug 21 are positioned to permit of their easy renewal, the plugs being of any suitable ma-

aterial especially adapted to resist the wear referred to.

The device thus constructed is adapted to wash pipe 19 back to the boiler by passing

5 water from pipe 18 thru valve 14, correctly positioned for that purpose, and thru port 16, and for washing out strainer 25 by passing water from pipe 18, valve 14, positioned for that purpose, thru port 17, port 23 in plug

10 21, strainer 25, channel 27, port 29, thru valve 31 to port 34 and pipe 35. The device is further adapted for directing the flow of blowdown water from pipe 19 thru the adjacent port or ports, thru valve 14, channel 11, channel

15 27, chamber 20, strainer 25, port 23, annular chamber 20, thru bore 47 of plug 46, and thence thru port 45 of plug 42, thru channel 38, valve 31, pipe 33, to a main continuous blowdown pipe, assumed to be employed in

20 the installation. Water for testing purposes may be drawn off at 35, by passing blowdown water from pipe 19 thru 16, valve 14, channel 11, port 29, thru valve 31, correctly positioned for that purpose to port or channel 34

25 and pipe 35.

The filtered blow down water can be used for any purpose for which it is suitable, depending upon the character of the water supplied to the plant, on the condition of the boilers, and on the care exercised in the use of the present apparatus. Use therefore includes flushing in general, flushing or cleaning any one of a battery of boilers with heated and filtered water from the main blowdown pipe, without drawing on the main supply,—and when the filtered water is sufficiently pure it can be returned to the feed water heater.

30 40 The ports provided in the plugs 21 and 42 reduced the pressure through the strainer, whether fluid is being admitted from the boiler through valve 14, or from the main blowdown pipe through valve 31, duct 38, and valve 42.

45 Further control of the pressure is effected by adjusting the position of plugs 21, 42, and they are thus capable of functioning as valves. Moreover, strainers of different surface extent or mesh can be employed as occasion requires, and they can be readily removed for cleaning and replaced. (The port of either of these plugs will be partly cut off upon outward movement of the plug, and under one of the conditions of use heretofore specified, the inlet for the strainer is through the valve port.)

50 Either filtered or unfiltered water can be drawn off at 35 for testing purposes.

55 60 Having described the invention what is claimed is:—

In a device of the class described, a housing having a plurality of inlet connections and outlet connections and having channels for the passage of fluid, said housing having two valve chambers, one chamber being in com-

munication with the plurality of inlet connections and the other with the outlet connections, valves within the chambers, a third chamber in the housing and a strainer in the chamber last named, said third chamber having communication with the channels and with a point of discharge, one of said valves communicating with the inlet connections and with those channels admitting fluid to the housing, and this valve controlling the flow, in either direction, through the strainer, thereby effecting straining or strainer-cleaning action, and a ported and adjustable plug mounting the strainer.

65 70 75 In testimony whereof I affix my signature. 80
